UNITED STATES PATENT OFFICE.

GEORGE H. BRUDER, OF FITCHBURG, MASSACHUSETTS.

INDICATOR FOR VEHICLES.

1,341,009.

Specification of Letters Patent. Patented May 25, 1920.

Application filed October 4, 1918. Serial No. 256,876.

To all whom it may concern:

Be it known that I, GEORGE H. BRUDER, a citizen of the United States, residing at Fitchburg, in the county of Worcester, State 5 of Massachusetts, have invented certain new and useful Improvements in Indicators for Vehicles; and I do hereby declare the following to be a full, clear, and exact description of the invention, such as will enable 10 others skilled in the art to which it appertains to make and use the same.

This invention relates to indicators for vehicles and it has for its object to provide an improved structure wherein the various 15 indicating members may be operated from a single manually actuated element.

In the present invention a semaphore is mounted and provided with means for swinging it to a plurality of indicating positions, selectively, there being in addition a target which upon adjustment and further movement of such means, is swung into active position as the semaphore is moved to neutral position.

25 In the embodiment of the invention which it has been elected to illustrate:—

Figure 1 is a perspective view showing the apparatus set to indicate the right-hand turn, the left-hand end portion of the attaching means being broken away.

Fig. 2 is a rear elevation of the structure shown in Fig. 1 with a portion of the tiltable bracket arm partly in section.

Fig. 3 is a bottom plan view of the bracket arm and its mounting, the wind-shield post being in section.

Fig. 4 is a vertical section taken from front to rear through the semaphore, the target, their casing and the bracket arm, 40 with the parts neutral.

Fig. 5 is a vertical section on line 5—5 of Fig. 4, and showing the rack and its mounting.

Fig. 6 is a transverse section on line 6—6 45 of Fig. 4.

Fig. 7 is a transverse section on line 7—7 of Fig. 5.

Fig. 8 is a perspective view illustrating the target and the double rack-bar, disconnected and illustrating the slot of the target and the pin of the rack-bar that strikes the bottom of the slot at times to swing the target.

Fig. 9 is a perspective view partly broken 55 away and showing the transverse bar that extends from the signal supporting bracket

to the opposite side of the wind-shield with its clamping means and with the operating lever and its latch, carried thereby.

Fig. 10 is a sectional view taken vertically 60 through the transverse bar shown in Fig. 9 and through the lever supporting bracket carried by it, a portion of the lever and associated parts being also in section, with the remainder in elevation.

Fig. 11 is a detail horizontal sectional view through the pitman that connects the operating lever with the horizontal rack-bar that actuates the pinion with which the vertical double rack-bar also engages.

Fig. 12 is an elevation of the bracket clamp with which the bracket arm is tiltably connected.

Fig. 13 is a section on line 13—13 of Fig. 12, showing the clamp member of the main 75 supporting bracket engaged with an upright of a wind-shield.

Fig. 14 is a view showing in perspective and disassembled, portions of certain of the parts, to illustrate the manner of connecting 80 them.

Referring to the drawings, the present invention is illustrated as mounted upon the wind-shield frame of an automobile which in the present instance includes uprights 85 20 between which is illustrated a board 21 that may be a part of the frame or part of the body of the vehicle or whatever else the general equipment may dictate.

The indicator illustrated comprises a 90 bracket arm 22 that is mounted, in the present instance, upon the right hand upright or post 20 of the wind shield through the medium of a clamp with which it has tilting connection that permits of adjustments, 95 as will be presently explained.

At the outer end of the bracket arm 22 which as illustrated, is hollow and open bottomed, there are spaced upwardly projecting casing members 23 and 24, registering one 100 with the other and the upper portions of which conform in outline to the semaphore employed, while their lower portions conform to the target employed.

A pivot pin 25 is mounted in the casing 105 members and pivoted on it is a semaphore 26, which is illustrated in the form of an arrow. The semaphore is in the form of a hollow sheet metal box having front and rear red glass plates 26', there being a solid 110 block 27 intermediate the ends of the semaphore that directly receives the pivot pin.

When the semaphore is in vertical position, which is its inoperative or neutral position, it may stand either erect or inverted.

When the operator of the vehicle contemplates turning to the right or to the left, the semaphore is correspondingly swung in a horizontal position to indicate the direction intended. To thus swing the semaphore, there is fixed at one side, concentric with its axis of oscillation, a pinion 29 which is engaged by a rack 30 at one side of a longitudinal slot 31 in a double rack-bar 32, and through this slot there passes also the pin 25 of the semaphore.

The front member 24 of the semaphore casing is at its lower portion spaced farther from the rear member 23 than at its upper portion so that there results a jog 33, above which the members are connected as shown.

In the jog 33 is a slot 35 in which is adapted to reciprocate, the upper narrowed end 36 of the double rack-bar 32, the lower end of which is slidably mounted in a slot 37 in the upper wall 38 of the bracket arm 22, which as stated, is hollow and open at its under side.

Passed from front to rear through the side walls of the bracket arm 22 is a shaft 39, upon which, between the sides of the bracket are sleeves 40 between which is rotatably mounted upon the shaft a pinion 41. The sleeves 40 are between cotter pins 40' engaged through the shaft 39 that serve to hold the shaft from sliding longitudinally from place and also to prevent the sleeves from sliding apart and permitting endwise movement of the pinion and shaft.

The pinion 41 lies within a slot 42 formed longitudinally of the lower end portion of the bar 32 and engages a rack 43 forming one side of the slot 42. Thus when the pinion is rotated in one direction, bar 32 will be raised to swing the semaphore with its headed end to the left and when the pinion is operated in the opposite direction, the bar 32 will be lowered to swing the semaphore with its head to the right, to correspondingly indicate the direction of progress contemplated by the operator of the vehicle.

To indicate the intention of the operator to stop, there is employed a target including an annular head 46 that is in effect a truncated or short cylinder having an opaque wall while its ends are formed of transparent or translucent plates 47 that are preferably red and from this cylindrical head there radiates a stem 48 which in the structure illustrated, is hollow. From front to rear through the stem 48, that is parallel with the axis of the cylindrical head, there are formed registering perforations 49 that receive the pin or shaft 25 on which is pivotably mounted the semaphore 26 so that the target, which hangs normally with its head downwardly between and in registration

with the casing members 23 and 24, may at times be swung laterally so that the axis of its stem 48 may be horizontal and the head may be exposed. To thus shift the target, it is provided with a slot 50 formed longitudinally of its stem and beyond the perforations 49 from the head of the target the lower end of this slot when the target is in neutral position, approaching the horizontal upper tangent of the corresponding perforation 49 of the target stem 48. Projecting from the double rack-bar 32 is a pin 51 that engages the slot 50 and lies midway between the ends of the slot when the semaphore and target are in neutral positions simultaneously.

It will be understood that if the rack-bar 32 is raised or lowered to a limited extent, the semaphore will be swung to point to the right or to the left in horizontal position, with the pin 51 having lost motion in the slot 50, the various parts being correspondingly proportioned. The proportions are such that when the rack-bar 32 has been lowered to effect a horizontal position of the semaphore, the pin 51 is against the lower end of the slot 50. Further downward movement of the rack-bar 32 then serves to move the semaphore to inverted position, through coöperation of the pinion 29 and rack 30. During this final movement of the semaphore, the pin 51 being spaced laterally from the shaft 25, said pin presses first on the lower end wall of the slot 50, from which it passes to the left-hand side wall in Fig. 8 as the head of the target swings gradually to the right, so that the target is finally swung with its head entirely exposed from the casing at the time the semaphore is inverted. When the rack-bar 32 rises, the semaphore is rotated to its erect or upright position and the pin 51 moves correspondingly first from the side to the end of the slot 50 and then upwardly in said slot, and the target is permitted to gravitate into the casing.

The manner of mounting the bracket arm will be described before the manner of reciprocating the rack 32, for the reason that some of the elements that actuate the reciprocating mechanism are carried by the same means that supports the bracket arm.

Referring to Fig. 1 of the drawings and Fig. 3, it will be noted that the side wall of the inner end portion of the bracket arm 22 are unconnected at their tops as well as at their bottoms, which latter has already been stated and that these side wall portions constitute gripping jaws 52 that are actuated through the medium of screws 53 to engage them upon the cylindrical body portion of a bar 54. The lower end portion of the bar 54 which is offset beyond the side face of the cylindrical body portion, is flattened and is perforated to receive a

5 pivot 55 that attaches it to the lower portion of the laterally directed face of an angle plate 56. At the upper edge of this face of the angle plate there is formed a flange 57 that overhangs said plate and is provided with a longitudinal slot 58 that is directed laterally of said face. Through this slot 58 extends the upper reduced end portion 59 of the bar 54, which portion is 10 threaded and receives a thumb nut 60 which by impingement against the flange 57, serves to hold the bar 54 at different points of its angular movement on pivot pin 55. The object of this particular arrangement will 15 be presently explained.

The plate 56 receives within its angle, in the arrangement illustrated, the right-hand post 20 of the wind-shield, in which position it is held through the medium of 20 an angular clamp plate including a wing 61 disposed slidably against that wing of the angle plate 56 having the flange 57 and in which position it is slidably held by headed fingers 62 that are struck from the angle 25 plate 56 and passed through the key-hole 63 in the wing 61 so that the wing 61 may move laterally of the contacting wing of the angle plate 56. The other wing of the angular clamping plate has its outer 30 edge portion bent to form a clamping jaw 64 that engages about the post 20, against the opposite side face of which rests the jaw 65 projecting from the corresponding wing of the angle plate 56. Clamping action of these jaws is effected through the 35 medium of screws passed loosely through the angle plate 56 and engaging threaded openings in the angular clamp plate.

The description just given develops the 40 reason for the swinging rod 54 on which the bracket arm is mounted. If the post 20 be not erect, but inclined rearwardly as often occurs, the rod 54, by adjustment on its pivot 55 may nevertheless be set in a 45 vertical position so that the semaphore and target will operate in a vertical plane, excepting as modified by the incline of the vehicle equipped.

As illustrated, the wing of the angular 50 plate 56 against which the rod 54 is pivoted, extends fore and aft of the vehicle while its other wing extends laterally and inwardly of the vehicle, and between this last named wing and the member 21 of the vehicle there is disposed a bar 67 which 55 is held to this wing by means of T-shaped fingers 68 that are struck from the wing and are engaged in key-hole slots 69 in the bar, the heads of which key-hole slots are 60 inwardly of the bar. The opposite end of the bar 67 is turned in the direction of the element 21 of the vehicle and provided with a slot 70 in which is slidably disposed a bar 71 having at its inner end a headed finger 72 projecting laterally therefrom first

through a key-hole slot 73 in the bar 67 and then through an elongated slot 74 in a bar 75 that overlies the bar 67, extends beyond the laterally turned end of it and is provided with a hook 76 at its end beyond the bar 67 which hook engages around the other post 20 of the wind-shield. The bar 71 has a narrowed threaded extension 77 passed through the base portion of the hook 76 and provided with a hand-nut 78 which when rotated serves to slide or to release bars 67 and 75, depending upon its direction of rotation. The sliding movement draws the hook 76 into close clamping engagement with the post 20. 70 75 80

The bar 67 carries a bracket consisting of a metal plate including a central or body portion 80 from one end of which extend lateral arms 81 having integral fingers 82 at their upper and lower edge portions 85 respectively that are engaged in hook form over the upper and lower edges respectively of the bar 67, thus to secure the bracket thereto.

From the lower portion of the body 80, 90 the plate extends rearwardly and upwardly and is then broadened as shown at 83 where it is provided with a transverse slot 82' above which, the plate is extended toward and at right angles to the body portion 80, 95 as shown at 83', its extremity being turned upwardly to lie against the body above its arms 81, where it is held by integral hooked fingers that engage about the side portions of the body above the arms. 100

Passed through the slot 82 is an actuating lever 85 that is pivoted at its inner end to the top 83 of the bracket and it is this actuating lever 85 that is manually operated to effect the various adjustments of the signal 105 elements. The lever 85 is operatively connected with the pinion 41 to rotate it in one direction or the other, through the medium of a link 86 which is pivoted to the lever and a rack-bar 87 connected with the link 110 86 and whose rack engages the pinion 41. The connecting rod 86 at one end, within the casing of the bar 67, is bent upon itself and secured in truncated triangular form and at the top of the truncated triangle is an upwardly directed headed finger 87' which normally lies in the narrowed portion of a key-hole slot 88 through the enlarged part of which the finger is introduced, the fit of the finger in the narrowed portion being 115 sufficiently loose to insure reciprocation of the rod 86 when the lever is swung from side to side. The base of the truncated triangle has a longitudinal slot 89 in which lies a headed pin 90 that projects from the body 120 80 of the bracket and holds the link slidably positioned. The link is slidably supported at its opposite end portion through the medium of a similar headed finger 91 that projects from the angle bracket and 130

lies normally within the narrowed portion of a key-hole slot 92 in the link. Beyond this key-hole slot, the link is turned laterally across the face of the angle bracket plate where it is bifurcated with resultant fingers 93 that engage in notches 94 formed in the upper and lower edges respectively of the rack-bar 87. The rack-bar 87 is slidably mounted in slotted guides 95 that depend from the top of the bracket arm 22 and hold this rack-bar in engagement with the pinion 41.

Now the slot 82 is of such length and position that when the lever 85 is swung to the left to contact with the end wall of the slot, the rack-bar 87 will have been correspondingly drawn to give the pinion 41 sufficient rotation to raise the rack-bar 32 and move the pinion 29 with the semaphore 26 an angular distance of ninety degrees. If the lever 85 be swung to the right until it contacts the other end wall of the slot 82, the bar 87, pinion 41, bar 32 and pinion 29 will be oppositely moved to carry the semaphore an angular distance of one hundred and eighty degrees from its normal, neutral or upright position, which effects inversion of the semaphore and setting of the target. In order to limit movement of the lever 85 to the right so as to correspondingly set the semaphore without setting the target, a stop is movably mounted on the lever at one side and normally is in position to contact with the right-hand end wall of the slot 82 and correspondingly limit the movement of the lever 85 in that direction. This stop is shown at 96 as projecting laterally from a plate 97 that underlies the lever 85 and has its outer end turned upwardly to form a thumb piece 98 which is slotted in its lower portion as shown at 99 and through the medium of which slot it is slidably mounted upon the lever. The plate 97 at its inner end portion lies below the top 83 of the lever supporting bracket and has an elongated slot 100 through which passes the finger 87 and to the inner extremity of the plate 97 is attached at one end, a spring 101 which is attached at its other end to the lever and serves to hold the plate 97 normally and yieldably with the stop 96 in position to engage the end wall of the slot 82. When the outer end of the lever 85 is grasped, the thumb may be pressed against the thumb piece 98 to slide the plate 97 and carry the stop 96 out of position to contact with the end wall of the slot 82, when the lever may be swung to the right to a distance sufficient to invert the semaphore and set the target.

The lever 85 is provided with an index 102 that overhangs the top 83 of the bracket and traverses a scale marked to indicate the active positions of the semaphore and target. When the lever is in position with

the indicating members at rest, it lies in a depression 103 midway of the ends of the lower side of the slot 82.

Within each end of the semaphore there is mounted an electric lamp 104 and 105 respectively while within the head of the target there is an electric lamp 106 which may have any desired source of energy with which they may be brought into circuit when their corresponding signals are active, 75 through whatever arrangement is desired.

What is claimed is:

1. An indicator comprising an indicating member movable into and out of indicating position, a second indicating member and 80 means for moving the second indicating member into indicating position upon movement of the first indicating member beyond its indicating position to unindicating position.

2. An indicator comprising an indicating member having a neutral position and reversely movable therefrom to indicating position, a second indicating member having a neutral position and movable therefrom to 90 indicating position and connections between the indicating members for movement of the second member to indicating position upon movement of the first member in one direction to indicating position in one direction 95 only.

3. An indicator comprising a pair of indicating members each movable into and out of indicating position, an actuating member disposed between the indicating members 10 and having permanent operative connection with one of them and means for operating the other indicating member when the operating member is actuated to carry the first named member beyond an indicating position.

4. An indicator comprising a pair of pivoted indicating members, a slideable bar mounted between the indicating members and permanently connected with one of them 11 for swinging it reversely into opposite indicating positions and for inverting it and means carried by the bar and engageable with the second indicating member to move it into indicating position when the bar is 11 moved to swing the first indicating member from indicating to inverted position.

5. An indicator comprising a semaphore pivotally mounted for movement to opposite indicating and to inverted positions, a pinion carried by the indicator, a movable rack-bar engaged with the pinion for reversely rotating it, a target pivotally mounted for movement into and out of indicating position and provided with a slot to offset laterally from its pivot and a pin carried by the rack-bar and lying within the slot, the pin having unobstructed movement in the slot when the rack-bar is reciprocated to move the semaphore to indicating position, 12

the slot and pin being correlative positioned to engage the pin with the bottom of the slot and swinging semaphore to indicate the position when the rack-bar is moved to 5 carry the semaphore beyond a direction indicating position.

6. A direction indicator comprising an indicating element pivotally mounted for oscillatory movement to opposite indicating 10 positions, a pinion coaxial with the indicating element and fixed thereto, a reciprocating rack-bar having a rack engaged with the pinion, a second pinion rotatably mounted, a second rack carried by a bar and engaged with the second pinion, a second rack-bar having its rack engaged with the second pinion and means for reciprocating the second rack-bar.

7. The combination with a direction indicating member mounted for oscillation into and out of indicating position and a support for the indicating member comprising a member that carries the indicating member and a second member adapted for attachment to a vehicle and with respect to 25

which the first named supporting member is pivotally adjustable in a plane at right angles to the plane of oscillation of the indicating member.

8. An indicator comprising an indicating member movable into and out of indicating position and a support comprising a member by which the indicating member is carried and an attaching member with which the carrying member is connected for adjustment in a plane at right angles to the plane of movement of the indicator into and out of indicating position.

9. An indicator comprising a pair of indicating members constructed and arranged for successive movement to indicating position, a lever, means operatively connected between the lever and the indicating members for actuating one of them under normal movement of the lever and for actuating the other of them upon a further movement of the lever and means for selectively limiting the movement of the lever.

In testimony whereof I affix my signature.
GEORGE H. BRUDER.
